UNITED STATES PATENT OFFICE.

WILLIAM H. FABREY, OF SCHENECTADY, NEW YORK, ASSIGNOR TO WEBER ELECTRIC COMPANY, OF SCHENECTADY, NEW YORK, A CORPORATION OF NEW YORK.

FUSE PLUG.

Application filed November 4, 1927. Serial No. 231,069.

The present invention relates to electric fuse plugs, and particularly to the means for securing the contact shell to the core in such devices.

Devices of this nature consist essentially of a body or core element of porcelain or equivalent insulating material, this body or core element consisting generally of a head portion and a boss portion, which latter is surrounded by a contact shell. The contact shell is threaded both exteriorly and interiorly, the latter threads being an incident to the former. Sometimes, according to prior practice, the boss portion of the core has threads molded in it for cooperation with the interior threads of the shell; again, the boss portion is frequently made smooth so that the shell will slip directly over it, and in this case, some further means must be provided to secure the two in permanent relation. In this latter practice, one method of securing the shell to the boss portion has been to provide the latter with indentations inwardly of the threaded portion of the shell, the latter having an extension sleeve which at points in register with the indentations of the boss, is pressed into such indentations.

The difficulty here has been to insure that the indentations would be directly in register with the pressing tools, and due to this difficulty, loss from breakage has been extremely high.

The present invention is concerned with the provision of means to obviate this pressing operation in the use of a smooth or unthreaded cylindrical boss and an interiorly threaded shell. The invention will be described with particular reference to the accompanying drawings, wherein:

Figure 1 is a central longitudinal section of a plug embodying the present invention;

Figure 2 is a section on the line 2-2 of Figure 1;

Figure 3 is a side elevation of the core or body element with the shell removed; and

Figure 4 is a perspective of the unit provided by the present invention for effecting the union between the core and shell.

Referring to the drawings, 10 represents generally the core or body portion of the plug, which, as here shown, consists of what may be termed a boss portion 11 surmounted by an annular shoulder 12, which, in turn, is surmounted by an expanded annular head

portion 13. The core is provided with an axially extending chamber 14 which, at the chamfered extremity 15 of boss 11, is closed by means of a center contact element 16. Contact element 16 has an inwardly extending sleeve portion 17 which, at its inner extremity, is expanded over a shoulder 18 so as to retain the contact element securely in position. Immediately beneath shoulder 12 the boss portion 11 is provided with a recess 19, as clearly shown in Figures 1 to 3, this recess being substantially rectangular as viewed from the side as in Figure 3. The axially extending passage 20 is primarily incidental to the molding of recess 19, although under certain circumstances, this passage may be utilized as a conduit for the fuse element of the plug. In the embodiment as shown, however, a second axially extending passage 21 is provided, which passage leads to a second recess 22 in the boss portion immediately below shoulder 12, and the end 23 of fuse element 24 is led into this second recess. The other end 25 of fuse element 24 is connected to the center contact element 16. Recesses 19 and 22 are preferably substantially diametrically opposed.

As a primary means for securing the contact shell 26 to boss portion 11 which, as shown, has no threads for cooperating with the interior threads of the shell, I provide a substantially arch-shaped element 27 adapted to be disposed in and seated against the back wall of recess 19 and to project therefrom in such a manner as to provide partial threads for cooperation with the inner threads of the shell. As here shown, element 27 is substantially M-shaped, the legs of this element resting on the bottom of recess 19 and being of such length as to position the shoulders outside of the peripheral bounds of the boss portion.

It will be readily apparent that element 27 can only be displaced radially and outwardly of the boss portion, and that when the shell is applied, all displacement is prevented. This element, as shown, is formed of strip material, preferably resilient, and while its projecting portion may be provided with any desired number of corrugations the form shown has been found to be entirely satisfactory.

After shell 26 has been screwed into proper position on the boss through cooperation with

what may be termed the filler piece 27, it still remains to establish connection between it and end 23 of the element 24.

A satisfactory manner of accomplishing this is to bond the two together by means of a drop of solder 28 introduced through passage 21. The solder will not only form a satisfactory connection, but will also serve as a locking lug to prevent rotation of the shell 10 relative to the core due to its engagement with the sides of recess 22. This, however, is merely a secondary precaution, since the frictional engagement of member 27 with the shell, enhanced by the resilient properties of 15 the former, will be sufficient under most circumstances to retain the shell in proper relation to the boss.

To complete the plug, a transparent disk 29 is placed over chamber 14 in a shouldered 20 seat 30, and finally an apertured cap 31 is crimped over head 13, the margins of the aperture overlying the edges of disk 29 in a manner to retain the latter in place.

While I have necessarily described a specific embodiment of my invention, it is to be understood that I do not limit myself except as determined in the following claims.

I claim:

1. In an electric fuse plug, a core element 30 including a substantially cylindrical boss portion, an interiorly threaded contact shell surrounding said boss portion, said boss portion being unthreaded and having a lateral recess, a filler piece seated in said recess and 35 having a portion projecting therefrom into screw-engagement with the threads of said shell and a fuse element in said core element.

2. In an electric fuse plug, a core element 40 including a substantially cylindrical boss portion, an interiorly threaded contact shell surrounding said boss portion, said boss portion having a lateral recess, a filler piece in 45 said recess and having a portion projecting therefrom into screw-engagement with the threads of said shell, a fuse element in said core and a common means serving to secure an end of said fuse element and to hold the shell against rotation.

3. In an electric plug, a core element including a smooth substantially cylindrical boss portion, an interiorly threaded contact shell surrounding said boss portion, said boss portion having a lateral recess, and a filler piece of strip metal in said recess having a 55 rib projecting from said recess and extending circumferentially relative to said boss portion, said rib being in screw-engagement with the threads of said shell.

4. In an electric plug, a core element 60 including an unthreaded substantially cylindrical boss portion, an interiorly threaded contact shell surrounding said boss portion, said boss portion having a lateral recess, and

a substantially arch-shaped filler piece in said recess formed of resilient strip material, the top of said filler piece projecting from said recess into screw-engagement with the threads of said shell. 65

5. In an electric fuse plug, a core element including a smooth substantially cylindrical boss portion, an interiorly threaded contact shell surrounding said boss portion, said boss portion having a lateral recess, a substantially arch-shaped filler piece in said recess, the top of said filler piece having a corrugation projecting from said recess and extending circumferentially relative to said boss portion, said corrugation forming partial threads in screw-engagement with the threads of said shell and a fuse element in 80 said core element. 70

6. In an electric plug, a core element including a smooth substantially cylindrical boss portion, an interiorly threaded contact shell surrounding said boss portion, said boss portion having a lateral recess, and a substantially resilient arch-shaped filler piece seated in said recess, the top of said filler piece having a corrugation projecting from said recess and extending circumferentially 85 relative to said boss portion, said corrugation forming a partial thread in screw-engagement with the threads of said shell. 90

7. An electric fuse plug comprising a hollow core element including a smooth substantially cylindrical boss portion, a central contact element at the extremity of said boss portion, an internally threaded contact shell surrounding said boss portion, said boss portion having a lateral recess, a filler piece in 100 said recess and presenting a partial thread for cooperation with the threads of said shell, and a fusible element in said hollow core element and secured to said central contact element and to said shell respectively. 105

8. An electric fuse plug comprising a hollow core element including an unthreaded substantially cylindrical boss portion, a central contact element at the extremity of said boss portion, an internally threaded contact shell surrounding said boss portion, said boss portion having two lateral recesses, a filler piece in one of said recesses and presenting a partial thread for cooperation with the threads of said shell a fusible element in said 110 hollow core element connected at one end to said central contact element and having its other end disposed in said other recess, and means bonding said other end of said fusible element and said shell and thereby forming a locking lug to prevent rotation of said shell 115 relative to said core element. 120

In testimony whereof I have hereunto set my hand.

WILLIAM H. FABREY.
